DESIGN FOR A COLLECTION BOX FOR SALES TAX

William Arthur Honeyman, San Anselmo, Calif.

Application February 21, 1936, Serial No. 61,292

Term of patent 3½ years

To all whom it may concern:

Be it known that I, William Arthur Honeyman, a citizen of the United States, residing in the city of San Anselmo, Marin County, State of California, have invented a new, original, and ornamental Design for a Collection Box for Sales Tax, of which the following is a specification, reference being had to the accompanying drawing, forming a part thereof, wherein—

The opposite side of the design in Figure 2 is of substantially the same configuration and appearance as the side shown.

The opposite side of the design in Figure 3 is of substantially the same configuration and appearance, with the exception of handle, as the side shown.

I claim:

The ornamental design for a collection box for sales tax, as shown and described.

In witness whereof I have signed my name to this specification.

WILLIAM ARTHUR HONEYMAN.
